UNITED STATES PATENT OFFICE

159,039

VALVE KEY INSERTER

Herbert A. Berkman, Chicago, Ill., assignor to
Zim Manufacturing Company, a corporation of
Illinois

Application May 24, 1949, Serial No. 2,856

Term of patent 14 years

(Cl. D54—13)

To all whom it may concern:

Be it known that I, Herbert A. Berkman, a citizen of the United States, residing in Chicago, in the county of Cook and State of Illinois, have invented a new, original, and ornamental, Design for a Valve Key Inserter, of which the following is a specification, reference being had to the accompanying drawing, forming a part hereof.

Fig. 1 is a top plan view of a valve key inserter, showing my new design;

Fig. 2 is a bottom plan view; and

Fig. 3 is a side view.

I claim:

The ornamental design for a valve key inserter, as shown.

HERBERT A. BERKMAN.
